UNITED STATES PATENT OFFICE.

FRANCIS G. ECHOLS, OF HARTFORD, CONNECTICUT, ASSIGNOR TO PRATT & WHITNEY COMPANY, OF HARTFORD, CONNECTICUT, A CORPORATION OF NEW JERSEY.

MOTOR MECHANISM.

SPECIFICATION forming part of Letters Patent No. 731,872, dated June 23, 1903.

Original application filed August 25, 1902, Serial No. 120,953. Divided and this application filed December 18, 1902. Serial No. 135,794. (No model.)

To all whom it may concern:

Be it known that I, FRANCIS G. ECHOLS, a citizen of the United States of America, residing at Hartford, in the county of Hartford and State of Connecticut, have invented certain new and useful Improvements in Motor Mechanism, of which the following is a specification.

My invention relates to motor mechanism; and it has for its object the provision of improved devices of this character for actuating a device in a reliable, quick, and accurate manner.

In the accompanying drawings, Figure 1 is a side elevation of part of a reamer-grinding machine containing my improvements. Fig. 2 is an end view of the head-stock of said machine. Fig. 3 is a horizontal section of the head on which my improved motor mechanism is mounted, taken on line $z-z$ of Fig. 1. Fig. 4 is a sectional view of the piston-chamber and the parts therein. Fig. 5 is a face view of the cover to the piston-chamber detached. Fig. 6 is a horizontal section of the valve-chamber, the valve being in elevation. Fig. 7 is a perspective view of the piston and part of the shaft thereof; and Figs. 8 and 9 are perspective views of brackets carrying adjustable stops, said brackets being mounted on the carriage of the machine.

Like numerals designate similar parts throughout the several views.

Referring to the drawings, the numeral 1 designates a frame of what is shown as a reamer-grinding machine, and 2 a carriage mounted for reciprocatory movement upon said frame. Mounted on this carriage is a table 3, secured to said carriage by bolts 4, passing through arcuate slots in the ends of 40 the table, and whereby said table may be adjusted angularly upon the carriage in a well-known manner should it be desired to adapt the machine to the work of grinding or relieving taper blanks.

Designated by 5 is a head-stock, and by 6 a tail-stock, each of said stocks being adjustably secured to the carriage by bolts 7. In the head-stock is mounted a tubular shaft 8, to which motion may be imparted in any de-

50 sired way, (not shown,) and secured to said

shaft 8 is a piston-chamber 9. Located within the shaft 8 is a shaft 10, having a crank 12 at one end and a piston 13 at its opposite extremity, said piston being within the piston-chamber 9. Also fitted in said piston-chamber 9 is an abutment 14, in which a port 15 is formed for the admission of compressed air or other motive fluid delivered to said port by a nipple 16, inserted in a recess of the piston-chamber and communicating with a pipe 17, leading to a source of supply. Passing through and threaded into the wall of the piston-chamber is a screw 18, upon which may be placed a jam-nut 19 for the purpose of securing said screw against movement 55 when it has been adjusted. This screw serves to limit the movement of the piston within the chamber by engaging a wing 13', projecting from the hub 13² of the piston, said hub being keyed to or otherwise secured to the 70 shaft 10, as illustrated in Fig. 4. At its open end the piston-chamber is closed by a cap or cover 20, having an arcuate slot 20' for the reception of a pin 21, carried by said wing 13' of the piston, and also riveted or otherwise 75 secured to said cover-plate 20 is a plate 22, through which the pin 21 passes, said plate serving to prevent leakage of air or other fluid employed through the slot 20'. Attached at one end to the pin 21 is a spring 23, 80 and projecting from the piston-chamber is a bracket 24, in a slot of which is a set-screw 25, this screw connecting said bracket with an adjustable arm 26, carrying a pin 27, to which the other end of the spring 23 is attached, as illustrated in Fig. 2.

Fitted in a guideway of the head 8' of tubular shaft 8 is a slide 28, said slide having a slot 28' for the reception of a pin 29, projecting from a flanged head 30 of the sleeve, 90 for actuating the mechanism to be operated, said mechanism being designated in a general way by the numeral 31. This mechanism consists in the exemplification given of a cup-like carrier 32, containing a pair of 95 friction-disks *a* and *b*, (shown by dotted lines in Fig. 3,) fully disclosed in my application filed August 25, 1902, Serial No. 120,953, of which the present case is a division.

On the frame of the machine is mounted a 100

bracket 33, carrying a valve-chamber 34, within which is located a valve 35 and a spring 36 for returning the valve after it has been actuated by means hereinafter described to permit fluid to pass to the pipe or conduit 17. Communicating with a port of the valve-chamber is a supply-pipe 37, and leading from another port of said chamber is a nipple 38, over which the end of the pipe 17 is secured, as illustrated in Fig. 6. At its ends the valve-chamber 34 is closed by perforated caps 39 and 40, respectively, and the valve 35 is connected to a rod 41, as illustrated in Figs. 1 and 6. Designated by 42 is a lever, (shown pivoted to the frame 1,) said lever being connected at its lower extremity to said rod 41.

Mounted on the carriage are adjustable brackets 43 and 44, respectively, containing screw-stops 45 and 46, respectively, and also pin-stops 47 and 48, respectively, as illustrated in Figs. 1, 8, and 9. Pivoted to the frame is a lever 49, carrying a pair of stops 50 51, which are actuated by the screw-stops 25 of the brackets 43 and 44, said lever constituting a part of mechanism, not necessary to be shown in this application, for controlling the movement of the reciprocating carriage, this mechanism being fully disclosed in my 30 application Serial No. 120,953 aforesaid.

Carried by the tail-stock 6 is a center 52 and by the slide 28 of head 8' is a companion center 53, said centers serving to support between them what is shown as a reamer-blank 54, the lands or ribs of which are to be relieved by a grinding or other tool. (Not shown.) One of the friction-disks (shown by dotted lines in Fig. 3) may be connected in any desired way with a reamer-blank—as, for 40 instance, by a lathe-dog 55, shown attached to said friction-disk by a clamp 56, which may be of any suitable kind.

While my invention is described as appertaining to a particular machine for relieving the teeth of fluted tools, yet it is distinctly to be understood that it is not limited thereto, for the improved motor mechanism may be employed in other machines without departure from the invention.

50 In the operation of my improvement the mechanism works as follows: When it is desired to operate the motor mechanism for the purpose of actuating either a blank or part of a machine or other article to which said mechanism may be applied, one of the pin-stops of the brackets on the carriage will come into contact with the lever 42—for instance, upon the movement of the carriage toward the left—and will engage said lever above its pivot, thereby rocking the same and throwing the valve to the necessary position to admit fluid to the valve-chamber 34, the fluid from said chamber passing through the pipe 17, the nipple 16, and port 60 15 in the abutment 14 of the piston-chamber 9, and thus imparting movement to the piston 13 in said chamber until such movement

is resisted by the impact of the flange 13' against the end of the adjustable screw 18. This movement of the piston of course carries with it the crank-shaft 10, and as said crank engages the wrist-pin 28' of sleeve 30 it will rock the carrier 32, secured to said sleeve, and through the connections described impart movement to the device or article to be 75 actuated. In this rocking movement of the piston the spring 33 was of course distended, and upon the completion of said movement when the carriage starts to return to the right and the stop is withdrawn from its engagement with the end of the lever 42 the spring 80 will force the valve to its closed position, and said spring 33 will by its connection with pin 21 return the parts to the position they occupied before fluid was admitted to the piston-chamber. At the limit of the movement of the carriage 2 toward the right the pin-stop will engage the pivoted lever 42 below its pivot, and consequently impart the same movement to the valve (i. e., move it in the 90 same direction) as was imparted to it by the pin-stop to the lever and valve when the carriage reached the limit of its stroke toward the left, as above stated. In this way upon the termination of the stroke of the carriage 95 for which the stops are set in either direction the valve is actuated to admit fluid to the piston-chamber and the blank is indexed by the mechanism controlled by such fluid.

My invention is not limited to the precise 100 devices shown for accomplishing the results set forth, nor is it limited to any particular means for reciprocating the carriage of the machine, nor to any particular construction of the piston-chamber, nor to the particular 105 connection of the parts with the mechanism to be operated.

Changes in the form and proportions of the parts may also be made without departure from the invention, and said invention is not 110 restricted in its use to any particular purpose, for it may be employed, as above stated, in various relations different from that shown.

Having thus described my invention, what I claim, and desire to secure by Letters Pat- 115 ent, is—

1. A motor comprising a shaft; a piston secured to the shaft and having a wing; a piston-chamber in which the piston and wing are mounted; means for supplying fluid under pressure to said chamber; a bracket projecting from the piston-chamber; an arm adjustably secured to the bracket; and a spring connected at one end to the piston and at its opposite extremity to said wing. 120

2. A motor comprising a shaft; a piston having a projection secured to the shaft; a piston-chamber; means for supplying fluid to said chamber; a slotted cover for the piston-chamber; a stud secured to the projection of the piston and passing through the slot in the cover; and a spring secured at one end to the stud and at its other end to a fixed support. 125 130

3. The combination, with a piston-chamber, of a piston in said chamber, said piston having a wing; a recessed, slotted cover secured to said chamber; a pin projecting from the wing through the slot of the cover; a disk fitted in the recess of the cover and through which the pin passes; and means secured to the pin for retracting the piston.

4. A motor comprising a piston-chamber; a piston within said chamber; a shaft to which the piston is secured; a wing on said shaft; means for connecting the shaft with a device to be actuated; an adjustable stop in the piston-chamber; means for supplying fluid under pressure to said chamber to actuate the piston in one direction; and a spring for retracting the piston.

5. A motor comprising a piston-chamber; a piston in said chamber; a shaft to which the piston is secured; an abutment within the chamber, and having a passage for the supply of fluid to said chamber; and a spring for retracting the piston against said abutment.

6. A motor comprising a piston-chamber; a piston within said chamber; a shaft to which said piston is secured; an abutment within the piston-chamber, and having a passage; means for supplying pressure fluid to said passage; a wing projecting from the piston; an adjustable stop for limiting the movement of the piston; and a spring for retracting said piston against the abutment.

7. A motor comprising a piston-chamber; a piston in said chamber; a shaft; a valve-chamber having ports; a pipe communicating with one of said ports and leading to a source of fluid-pressure; a valve provided with a passage and ports entering said passage; means

for actuating the valve; and a conduit leading from the valve-chamber to the piston- 40 chamber.

8. A motor comprising a piston-chamber; a piston in said chamber; a shaft; a fluid-supply conduit leading to the piston-chamber; a valve-chamber having ports; a valve in said 45 valve-chamber, said valve having a longitudinal passage and ports opening therefrom; a pressure-supply pipe communicating with one of the ports of the valve-chamber; a conduit leading from the port of said valve-chamber 50 to the piston-chamber; a valve-actuating rod; and a spring for retracting the valve.

9. A motor comprising a piston-chamber; a piston in said chamber; a shaft; a pressure-supply pipe leading to the piston-chamber; a 55 spring connected to the piston and serving to retract the same after the supply of pressure is cut off; a valve-chamber having ports; a valve having reduced portions, a longitudinal passage, and ports in said reduced portions 60 leading from the passage; a valve-rod; a spring surrounding said rod, and bearing against the head of the valve-chamber and the end of the valve; means for actuating the valve-rod; a pressure-supply pipe leading to 65 one of the ports of the valve-chamber; and a conduit communicating with the other port of said valve-chamber and with the piston-chamber.

In testimony whereof I affix my signature 70 in presence of two witnesses.

FRANCIS G. ECHOLS.
